UNITED STATES PATENT OFFICE

2,542,307

PIANO ACTION

Alexander P. Brown, Beechhurst, N. Y.

Original application September 30, 1947, Serial No. 776,987. Divided and this application June 2, 1949, Serial No. 96,793

5 Claims. (Cl. 84—240)

1

This invention relates to piano actions.

It is well known in the arts of small vertical pianos that the piano actions are large, deep and much below the level of the manual keys; these are known as underslung actions. It is known that in most of these types it is necessary to have certain levers or connections from the key down to the wippen. These connecting levers are known to have a flexibility or a give, which causes an unsatisfactory mushy touch.

Also in the present vertical type piano actions, the jack usually has a compression spring located under the front knuckle portion of the jack, and the said spring is secured by glue in the front portion of the wippen. This former construction requires a separate jack flange with its edge glued into the wippen so as to provide space for the compression front jack spring. These flanges are objectionable not only because they very often loosen and cause difficulties, but the jack flanged sections must be built larger and thus take up much valuable space in the pianos.

Further, the present back stop parts with the extension shank in the butt take up considerable space.

Further, the present actions for upright pianos have a spring for the hammer and one separate spring for the damper lever.

Further, when the present sostenuto pedal is in use, the certain awkward and annoying resistance occurs in the touch by the subsequent keys being played, which is due to the unyielding sostenuto rail or its cord when the sostenuto rail meets edge to edge with the sostenuto lever, or to the unyielding sostenuto lever and its rail contacting portion.

The piano-fortes to which the following invention is applicable though they all belong to the same class may still be of various construction.

The improvements include (1) the provision of the jack regulation screw in an exposed position permitting easy access for regulating it, by placing the abstract, the demountable bridle tape, the bridle wire, and the back check behind the said regulation screw, in which the pivoting of the lower portion of the abstract may be either directly to the jack or directly to the wippen; (2) the provision of a jack spring acting on the rear portion of the jack and supported by the wippen or its flange, (3) the radius head on the jack, enabling a fuller and solid blow, and step by step movement with a more rapid trip; (4) the back stop unit as part of the hammer butt, instead of separate widely spaced assembled parts of the present hammer butt, and a synchronizing back check; (5) the combination abstract guide and

2

lost motion compensator; (6) this combination supported by a flange secured to the hammer lift rail; (7) the action frame with holes to regulate the height of wippen guide lever and its rail and acting as an adjustment for different heights of piano, still retaining the standard key board height; with this, it will not be necessary to use different sizes of action frames for different heights of pianos; (8) the improved combination 10 sostenuto lever and damper lever using only one regular damper lever spring, this improvement having application to many type of pianos.

The improved compact action of small compass 15 still retains the time tested full length hammer shanks and the full size component parts. The straight pull of the abstract avoids the mushy touch and its new lower pivoting located in back of the jack trip regulation screw, requires less space. The hammer is driven more directly and 20 comes back faster than that of the old type of action. With the set of flanges on the hammer lift rail supporting the activating levers, a variable output of volume of tone is achieved, and a 25 constant touch depth is obtained, and the lost motion is compensated and taken up.

The invention will be more fully described hereinafter, embodiments thereof shown in the drawings, and the invention will be finally pointed out in the claims.

30 In the accompanying drawings,

Fig. 1 is a side view with parts in section showing embodiments of the improvements;

Fig. 2 is a plan view of the demountable bridle tape, with its laminated ends;

35 Fig. 3 is a detail side view of the connection of the jack with wippen, substantially like the parts shown in Fig. 1, but somewhat modified in the construction eliminating the abstract and showing a modification in the rear jack wippen connecting spring;

Fig. 4 is a side view with parts in section, showing a modified embodiment of the invention disclosed in the embodiment of Fig. 1;

Fig. 5 is a vertical section taken on line 45 of Fig. 6;

Fig. 6 is a side view like that of Fig. 3, showing a common pivot for the abstract, jack and wippen, though the abstract may be omitted, and a modified construction of the rear spring; and

50 Fig. 7 is a view showing the flange at the lower part of the rail.

Similar characters of reference indicate corresponding parts throughout the various views.

Referring to the drawings, and more particularly to Fig. 1, the known key 1 of a piano has a capstan screw 2. A last motion compensating

abstract guide lever 3 has a felt lining 3a, and rests upon the capstan screw 2. The curvature of the lever permits a compensating action. The lever 3 is pivoted at 3b to a flange 4, which is supported by and secured to the hammer rail 5, by screws 5a, which rail 5 has a felt layer 5b thereon. The rail 5 is movable upwardly and towards the string 60 by a lift dowel 7 as known, and returns by gravity. To the rail 5, a pivot rod 8 is pivoted at one of its ends, and the other end of the rod 8 is pivoted to a fixed action frame 9 having spaced ports or openings 90, any one of which may be selected for the proper piano keyboard height regulation of the rail 5. Only a portion of the action frame 9 is shown as it is well known without the spaced openings. All of these parts are so constructed that their location is at the rear or back of a jack strip regulation screw 28a and button 28.

The jack 24 has a felt inlay or blocking felt 25, to soften the thrust of the jack against the wippen, and has a knuckle portion 27 to impinge against the felt covered regulating button 28 of a screw 28a, supported on a rail 28b. To the jack 24 at its lower rear portion at 26 is movably inserted one end of a rear jack spring 31, which is preferably bent up to form a convolution, and has its other end secured to the wippen 32. The wippen 32 is pivotally supported at 34a to a wippen flange 34 secured by screws 34b to an action rail 37. The wippen 32 supports a spoon 33. A spring 35 preferably of the coiled type is disposed between the wippen 32 and a touch spring regulating rail 36 held movably by a screw 36a on the rail 37.

The butt 12 is pivotally connected at 68 to a hammer butt flange 42 secured by screws 42a to the rail 37. The lower part of the butt 12 is curved and the upper end of the jack 24 abuts against it. A full motion butting or radius jack head 23 extends laterally of the upper end of the jack. The upper end of the jack 24 with the lateral extension or radius jack head 23 serve to press the butt upwardly and is released from the butt when the jack knuckle 27 abuts against the trip regulation button 28. A buckskin 12a with a cushioning felt 12b softens the pressure of the jack. A felt 12c limits the movement of the jack, so that the abutting end of the jack with its radius extension fits directly under the curved portion of the butt. The curved surface of the butt and the pivot 68 form substantially a horizontal line. The jack 24 moves substantially in a vertical direction, and thus swings the butt 12 on its pivot 68 to the extent of its thrust. When the jack is tripped, its upper end is moved completely out of contact with the buckskin 12a, while the butt is being held by the back check. The spring 31 returns the jack 24, when the pressure on the key 1 has been released as known.

A spring 66, preferably coiled at 66a, has one end engaged with the rear part of the butt 12 at port 63, being controlled by the spring tension regulating screw 13, and its other end engaged with the port 44 of the sostenuto lever 45, said lever having also a spring tension regulating screw 13a. The lever 45 is pivoted at 62 to the flange portion 39a of the damper lever 39 and extends upwardly to form the sostenuto lever engaging head 46, and one portion extends downwardly to engage the sostenuto lever rest felt 43 inlayed on the damper lever 39. This damper lever 39 is pivoted at 67 to a flange 41 secured by screws 41a to the rail 37, said damper extends downwardly and is provided with a felt

inlay 40, adapted to be engaged by the spoon 33, above which a damper lifting rod 38 is disposed. The damper lever 39 supports a wire 59, which supports the damper block 58 and felt 58a, which dampens the string 60 as shown.

Supported on the frame 9 and pivoted at 55 is a sostenuto rail actuating lever 53, one end 56 of which is accommodated to a dowel 57 suitably operated by a foot pedal in the known manner and not shown. The other end of the lever 53 has a felt washer 51 disposed between it and the screw head 52, and below that end of the lever, and between it and block 48, is a spring 50. A pivot rod 54 engages one of the ports 90 of the frame 9 and is connected with the block 48 on a rail 47 having a reinforcing part 48a and a bumper felt 49 against which the damper wire 59 strikes. The sostenuto rail 47 extends downwardly to cooperate with the sostenuto lever engaging head 46.

In the sectional view, Fig. 3, is shown the cut-out 32a in the wippen 32 to provide movement space for the lower part of the jack 24 which is curved as shown at 24a, a similar construction being used in Fig. 1. The modification shown in Fig. 3 is in the attachment of the spring and in the absence of the abstract 29, lever 3 and flange 4, and the provision of the felt 3a when actuated by a key in the well known manner. The end of the rear jack spring 31 which engages the wippen 32 directly in Fig. 1, now is secured in the flange 34 supporting the wippen 32.

In Fig. 4, the modification in respect to Fig. 1, consists in this: The damper bumper rail 48b with its felt layer 49 is fixed to the frame 9, by a screw 48c. The demountable bridle tape 16 has its lower end secured to the pin head 19 located on the lower end of the abstract 29 by a fastening pin 18. The butt 12 has a wire 21a bent downwardly to form a back stop portion 14a to abut against the felt 20b of the back check head 20a, now part of the jack 24. The rear jack spring 31 has one end now secured to the lower end of the wippen supporting flange 34. The spring 66a has one end now secured at 64 to the damper lever 39, provided with a spring channel 65. At the lower end of the damper lever 39, the sostenuto lever 45 is pivoted at 62, and is adapted to be pressed against the felt 43, which is secured to the damper lever 39, and extends downwardly to form the sostenuto engaging head 46. The sostenuto pedal operating rail 47 is supported on a sostenuto safety bumper spring 50, on the pedal operated dowel 57. The rail 47 is supported by a sostenuto pivoting rod 54, pivoted at 54b to a flange 34. A spoon bumper felt 40 is applied to the damper lever 39 to cooperate with the damper lifting rod 38 and damper spoon 33.

In Fig. 6, the modification consists in having the jack 24 and the lower end of the abstract 29 pivoted to the wippen 32 at 61, and the rear jack spring 31 extends from the rear end of the wippen 32, having its extreme end secured as at 31a to the lower end of the wippen 32 extending movably into the rear jack spring port 26 of the jack 24. A section taken on line 5—5 of Fig. 6, is shown in Fig. 5, to show the connection of jack 24 and abstract 29. The lower side of the wippen 32 has a felt 3a to coact with the keys 1, when the abstract 29, lever 3 and flange 4 of Figs. 5 and 6 are omitted.

In the improved constructions, the spring 66 in Fig. 1 is caused to perform three or less important distinct pressure functions, one pressure to bear

a very light pressure on the sostenuto lever 45, at spring port 44 to hold the sostenuto lever 45 yieldingly in its motion and in its position. Another function is to indirectly bear its full strength upon the damper lever 39, which exerts the required pressure through felt 58a against the note strings 60 to stop the string vibration. Another function is the medium regulatable pressure exerted on the hammer 10 through the butt 12, the spring 66 contacting the butt spring port 63 and is regulatable by screw 13.

The spring action principle is adaptable to any model piano action. Whenever it is desired to sustain the tone of any given numbers of keys, the performer strikes the piano keys 1, and immediately follows by depressing the sostenuto or center pedal, not shown, which activates the sostenuto rail 47. This rail 47 engages and holds the sostenuto lever tip 46, and thus holds the damper felt 58a away from the note string 60, as long as the pedal is held down by the performer's foot; during this interval other notes may be played to the performer's desire or content. The sostenuto lever tip 46 yieldingly contacts with the sostenuto rail 47 without the feel of that objectionable resistance or sluggish feeling in the keys as in the present sostenuto piano touch. This resistance is avoided because of the very light spring pressure upon the sostenuto lever 45 through the spring 66 in the port 44 and in the arrangement shown in Fig. 4. The sostenuto lever tip 46 yields against the sostenuto rail 47, thus the performer will have a smooth, even, satisfactory touch in the manual keys 1.

It will be noted that the vertically disposed damper lever adjacent the vertical strings forms one lateral boundary member of the improved action. The abstract forms the opposed lateral boundary member. The wippen forms the lower boundary member. Centrally disposed between the boundary members is the jack, butt, hammer and back check. The jack tripping regulation button is exterior of this grouping and laterally exterior to the abstract, that is, to the entire action. This compact small spaced assembly is made possible by pivoting the abstract direct to the jack or direct to the wippen; by providing the jack with a rear spring engaging portion into which a curved spring (in distinction to coiled springs) fits to operate the jack; and by the springs for the butt and damper lever.

As stated the abstract guide 3 supports the abstract 29, and the curbed surface 3a acts as a lost motion compensating lever. The distance from pivot 29a to pivot 35 is fixed, but by shifting the contact point between the surface 3a and the capstan screw 2, the leverage between that and the pivot 29a is changed to the distance of the hammer from the string, thus maintaining a constant touch depth between the key and the touch punching or bumper (not shown in the drawings) as these parts are known. Thus, the part 3, has the functions of an abstract guide, a lost motion compensator, and a constant touch depth governor, combined in one structure. With a constant input of energy upon the key, a variable output of tone is obtained by shifting the flanged hammer rail to its desired position, while lost motion, abstract guiding, and constant touch depth is obtained in every position of the hammer rail.

This is a division of my patent application Serial No. 776,987, filed September 30, 1947.

I wish it to be understood that I do not desire to be limited to the exact details of construction

shown and described, for obvious modifications will occur to a person skilled in the art.

I claim:

1. In a piano action having a rail, a wippen with its rear end pivoted to the rail and having a free front end, and a jack pivoted to said wippen at said front end, the combination of a knuckle portion on said jack extending beyond said front end of said wippen, and a jack trip regulation screw disposed above said knuckle portion and spaced from said knuckle portion to be engaged by said knuckle portion for tripping the jack, said jack and said front end of said wippen being between said regulation screw and said rail.
2. The structure of claim 1 in which a back check is disposed between said jack regulation screw and said jack.
3. In a piano action having a rail, a wippen with a rear end pivoted to said rail, and a free front end, a jack pivoted to said wippen at said front end, a pivoted butt, and a jack regulation screw, the combination of a flange portion extending upwardly of said front end wippen, a back check wire having a lower and an upper end, with said lower end on said flange portion, and said wire extending upwardly therefrom, a back check on said upper end of the wire, a wire having an upper and a lower end with its lower end on said butt, a bridle tape connecting the upper end of the back check wire with the upper end of the wire on said butt, said wire on said flange portion being between said jack regulation screw and said jack.
4. In a piano action having a rail, a wippen with a rear end pivoted to said rail, and a free front end, a jack pivoted to said wippen at said front end, a pivoted butt, and a jack regulation screw, the combination of a flange portion extending upwardly of said front end wippen, a back check wire having a lower and an upper end, with said lower end on said flange portion, and said wire extending upwardly therefrom, a back check on said upper end of the wire, a wire having an upper and a lower end with its lower end on said butt, a bridle tape connecting the upper end of the back check wire with the upper end of the wire on said butt, said wire on said flange portion being between said jack regulation screw and said jack, and an abstract supported on said flange portion above said pivotal connection of said jack with said wippen and between said jack regulation screw and said jack.
5. In a piano action, having a rail, a wippen pivoted at one end to said rail and having a free front end, the combination of a jack pivoted to said free front end of said wippen, and a spring extending from said pivoted end of said wippen to the rear of the jack and contacting therewith at a part between said pivotal connection of said jack with said wippen and said pivotal connection of said wippen with said rail.
